UNITED STATES PATENT OFFICE.

GEORGE WRAY AND ARTHUR WRAY, OF KEIGHLEY, ENGLAND.

APPARATUS FOR DAMPENING, MOISTENING, OR HUMIDIFYING FABRICS AND THE LIKE.

1,235,511.

Specification of Letters Patent. Patented July 31, 1917.

Application filed May 4, 1915. Serial No. 25,821.

To all whom it may concern:

Be it known that we, GEORGE WRAY and ARTHUR WRAY, subjects of the King of Great Britain, and residents of Alexandra 5 Shed, Keighley, in the county of York, England, have invented a certain new and useful Improvement in Apparatus for Dampening, Moistening, or Humidifying Fabrics and the like, of which the following description, having reference to the accompanying 10 sheets of drawings, is a specification.

In the finishing and treatment of fabrics for many and varied purposes it is often necessary that said fabrics should be moistened or made damp in order that the subsequent treatment to which said fabrics are subjected may produce the desired effects thereon. This moistening or humidifying of the fabrics must be effected on all the 15 parts thereof to an equal extent otherwise the subsequent treatments do not produce the desired results, and the devices heretofore employed for carrying out said operations or process have not been entirely reliable on account of certain parts being subjected to 20 more moisture or water than are other parts of the fabric passing through the apparatus. To produce mechanism or devices that will treat all parts or portions of the 25 surface of the fabric equally so that the damping or moistening of the whole of the fabric passing through the apparatus is carried out in every part thereof to the same extent and that by devices that may be 30 regulated to increase the humidity or decrease same according to what the fabric being treated may require, is the object of 35 our present invention.

In the accompanying sheets of drawings, 40 which are illustrative of our invention:—

Figure 1 is a side elevation of a machine constructed in accordance therewith.

Fig. 2 is a sectional side elevation thereof.

Fig. 3 is a back or rear elevation of said 45 machine.

Fig. 4 is a drawing in detail showing the device for controlling the operations of the several parts of the machine.

Fig. 5 is an end elevation of a sliding 50 pinion and the means for moving it as hereinafter explained.

Fig. 6 is a front view thereof.

Fig. 7 is a similar view to Fig. 2 and shows a slight modification in the arrangement of the fabric guiding roll and the 55 spraying device.

To attain the object of our invention we arrange appropriately shaped framework A for supporting the several parts of our apparatus. In bearings carried by said framework A we arrange a shaft *a* upon which is fixed a pulley *a'*. Upon a certain part of this shaft *a* we form a key or spline *a*² and taking loosely over said shaft *a* is a pinion *b* provided with a key-way *b'* which engages 60 with said spline *a*. When in the position indicated by Fig. 3 the shaft *a* is capable of revolving freely without transmitting motion to the pinion *b*; however as the pinion *b* is moved toward the pulley *a'* by 70 the means hereinafter described it engages with the spline *a*² and is capable then of transmitting motion to the gear wheels *c*, *d*. The pinion *b* is broad enough to gear either with the wheel *d* only or with both wheels 75 *c* and *d* simultaneously, said wheels *c*, *d* being placed out of alinement with each other for the purpose hereinafter described. To the wheel *c* is fixed another wheel *c'* 80 gearing with a wheel *e* fixed upon the shaft *f'* of the roller *f*. Upon the shaft *f'* is fixed a pulley *f*², a belt *f*³ taking thereover and around guide pulleys *g*, *g'* and a pulley *h'* mounted upon the shaft *h* of the roller *h*² at the opposite end of the machine to the 85 roller *f*; thus both the rollers *f* and *h*² are rotated from the gear wheel *c*.

Upon the shaft *d'* of the wheel *d* is mounted an eccentric *k* which by means of the rod *k'* operates a piston within the pump chamber *k*², this latter being connected by the pipe *k*³ with the vessel or accumulator *m* which acts as a store for water under pressure. Leading from the vessel *m* is a pipe *m'* having branches *m*², *m*³ which extend 90 over the top of the apparatus as shown by Figs. 1 and 2, and are provided with nozzles *m*⁴ which are so arranged as to give a very fine spray upon the fabric *x* as it passes from the roller *f* to the roller *h*², such spray 100 extending across the full width of the fabric.

In bearings on the framework A is arranged a shaft *n* upon which is fixed a lever *n'*, this being for engagement with notches *n*², *n*⁴, *n*⁵ in an arc shaped bracket *n*³ fixed upon said framework A and within which the shaft *n* may freely rotate or oscillate. Upon the shaft *n* is fixed a pinion *o* which gears with a rack *o'* sliding 1 upon a fixed bracket *o*². To the rack *o'* is connected a bifurcated piece or fork *o*³ which takes within a groove formed near

the end of the pinion b ; hence as said pinion o is rotated this bifurcated part o^3 will move the pinion b so that it will engage with the spline a^2 and so transmit rotary motion from the shaft a to the wheels c and d and so to the rollers f and h^2 and to the pump rod h' . Also mounted on the shaft n is a cam p having a cam slot p' in which a pin p^2 mounted at the end of the lever p^3 engages, said lever p^3 being fulcrumed at p^4 on a bracket p^5 fixed to the framework of the machine. To the upper end of the lever p^3 is connected a rack q which slides freely in a groove at the upper end of the bracket p^5 ; this rack q gears with pinions q' , arranged at the ends of the spindles of the valves q^2 , these latter being mounted in the branch pipes m^2, m^3 ; thus as the shaft n is rotated to cause the operations of the machine to be commenced, the cam p causes movement to be transmitted to the rack q to open the valves q^2 by means of the pinions q' and so start the operations of the spraying nozzles m^4 . The pinions q' may be slideable upon their spindle so that one or another of them may be passed or moved out of gear with the rack q ; thus either one or two nozzles may be operated at any time, and the valves q^2 are preferably arranged so that the nozzles m^4 give different strengths or quantities of spray upon the cloth x . Stop valves q^3 are mounted in the pipes m^2, m^3 so that the spray may be arrested from either of the nozzles m^4 whenever desired, such as when the machine is in motion. The number of pipes m^2, m^3 and nozzles m^4 may be varied as desired, although for most purposes we find that two pipes are sufficient.

At the base of the machine we arrange a tank r fed by a pipe r' and provided with an ordinary ball valve arrangement r^2 whereby the water contained in said tank is kept at the desired height. The pipe r' may be fed from any suitable source such as the ordinary town's water main. A feed pipe h^8 leads from the part r^3 of the tank r to the pump chamber h^2 , a non-return valve being mounted at h^5 for purposes well known, another non-return valve h^6 intervening between the pump chamber h^2 and the vessel m . The tank r has a chamber r^3 the wall r^4 of which is formed of porous material for the purpose of filtering the water passing therethrough to the feed pipe h^8 .

Beneath the cloth or fabric x we mount trays s which conduct any moisture or liquid falling from said fabric back to the trough or receptacle s^2 , whence it falls by the waste pipe s^2 into the tank r , this latter, if desired, being placed within an additional tank s^3 .

The fabric x is placed upon the support or "scray" t and is brought over the bars 1 and bars or rollers 2, around the rollers f

and h^2 , in manner above described, and then over the roller f carried by lever arms t' fulcrumed upon the shaft t^3 . The lever arms t^2 are oscillated from the shaft h by means of the pinion t^4 fixed upon the shaft h and gearing with a crank wheel t^5 , a connecting rod t^6 transmitting motion therefrom to the lever arm t' , this arrangement being old and well known for the purpose of folding, plaiting or "cutting" the fabric 75 or the like upon the support or "scray" t , beneath the roller t' . A roller w is mounted in bearings w' and assists in supporting the fabric x as it passes from the roller f to the roller h^2 .

By the wheels c and d being placed out of alignment with each other the lever arm n' may be moved from the notch n^4 (which it occupies when the machine is out of operation) to the notch n^2 which has the effect of 85 bringing the pinion b into gear with the wheel d to pump water into the vessel or accumulator m until the desired pressure is attained. The handle n' is then moved into the notch n^2 by which movement the pinion b will then gear with both the wheels c and d so as to start the rollers f and h into motion to drag or carry the fabric x through the machine. During the latter movement the cam groove p' causes the valves q^2 to be 95 opened (or one such valve to be opened), thus the fabric will then be traversed as desired through the machine to receive a continuous spray of liquid, the pressure being kept up by the operations of the 100 pump h^2 .

An observation opening z (which may be covered by glass or other transparent material or substances) is formed in the cover 3 in order that the operator may see that the 105 apparatus is working properly, while a hinged cover 4 is arranged at the rear of the apparatus by raising which access can be had to the roller f . We employ a pressure gage 5 and a relief valve 6 in connection 110 with our improved apparatus.

In Fig. 7 we have shown the roller f mounted in a more forward position than it occupies in the other sheets of drawings, while the nozzles m^4 are mounted at the rear 115 of machine. These nozzles can perform their functions upon the cloth x as it traverses from the roller a to the roller h^2 as in the above cases, but should one or other of the nozzles m^4 leak or liquid drop from the 120 pipes m^2, m^3 such drops cannot fall upon the cloth x as would be the case should such leakages occur when the roller f and nozzles m are mounted in the relative positions illustrated by the other drawings. The 125 roller f is rotated in the manner as is shown by Figs. 1 and 3.

If desired we may dispense with the valves q, q and the means for automatically operating them on the movement of the device for 130

putting the machine into motion and employ only the valves *g*.

Such being the nature and object of our invention what we claim is:—

- 5 1. In apparatus for damping, moistening or humidifying fabrics or the like, means for traversing said fabrics through said apparatus at a regular speed, a liquid supply vessel, a connection therefrom to a pump, an 10 accumulator, a connection thereto from said pump, a spraying nozzle, a connection thereto from said accumulator, a device for reciprocating said pump, means for bringing into action said traversing mechanism, means for 15 bringing into action said pump, and a connection between said means for bringing said pump and said fabric traversing mechanism into action at different times, substantially as herein specified.
- 20 2. In apparatus for damping, moistening or humidifying fabrics or the like, means for traversing said fabrics through said apparatus at a regular speed, a liquid supply, an accumulator for said liquid, a pump intervening between said liquid supply and said 25 accumulator, means for reciprocating said pump, nozzles mounted at the upper part of said apparatus, pipes leading thereto from

said accumulator, valves mounted in said pipes, a device for causing the pump to be brought into operation, a device for bringing into action the fabric traversing mechanism, and a device for opening and closing said valves, all these three devices being regulated from one source, substantially as 35 herein specified.

3. In apparatus for damping, moistening or humidifying fabrics or the like, means for traversing the fabric through the machine, spraying nozzles, a pump for supplying liquid to said spraying nozzles, means for transmitting motion to the fabric traversing devices, means for bringing the pump into action and a device operated by a single handle for bringing the pump and fabric 45 traversing mechanism into action at different times.

In testimony whereof we have signed our names to this specification in the presence of two witnesses.

GEORGE WRAY.
ARTHUR WRAY.
